TELEPHONE DIALING PENCIL

Everett Frooks, Plandome, N. Y.

Application February 17, 1955, Serial No. 34,558

Term of patent 3½ years

(Cl. D74—24)

Fig. 1

Fig. 2.

Fig. 3.

Figure 1 is a side elevational view of a telephone dialing pencil showing my design.

Figure 2 is a top plan view of the telephone dialing pencil shown in Figure 1.

Figure 3 is a front elevational view of the telephone dialing pencil shown in Figures 1 and 2 taken from the pencil point end.

I claim:

The ornamental design for a telephone dialing pencil, substantially as shown.
